JAMES E. SHRADER, OF EDGEWOOD, PENNSYLVANIA, ASSIGNOR TO WESTINGHOUSE ELECTRIC AND MANUFACTURING COMPANY, A CORPORATION OF PENNSYLVANIA.

GAGE FOR LOW PRESSURES.

1,346,427.

Specification of Letters Patent. Patented July 13, 1920.

Application filed December 27, 1917. Serial No. 203,195.

To all whom it may concern:

Be it known that I, JAMES E. SHRADER, a citizen of the United States, and a resident of Edgewood, in the county of Allegheny and State of Pennsylvania, have invented a new and useful Improvement in Gages for Low Pressures, of which the following is a specification.

My invention relates to new and useful improvements in gages for measuring low pressures of gases and vapors and more particularly to an improved form of gage of the radiometer type and somewhat similar to the well-known Knudsen gage.

One of the primary objects of my invention consists in constructing a gage of this character which operates by differential molecular bombardment of a movable metallic strip caused by heating a fixed metal strip disposed adjacent and parallel to the normal position of the movable film.

A still further object of my invention resides in providing a gage possessing extreme sensitiveness at low pressures which shall, at the same time, be simple and rugged in construction and easy of operation.

Another object which I have in view is the construction of a gage which, at low pressures, will operate independently of the nature of the gases or vapors being measured.

With these and other objects in view, my invention will be more fully described, illustrated in the drawings, and then particularly pointed out in the claims.

In the drawings, Figure 1 is a side elevation of my improved gage; Fig. 2 is a front elevation; and Fig. 3 is a fragmentary side elevation showing a slight modification in construction.

In the several views of the drawing and throughout the description, like parts are indicated by corresponding reference numerals.

My improved gage includes a body 10, preferably substantially cylindrical in shape and formed of glass, having a sealed-in supporting stand 11 at its lower end and a drawn-out sealed upper end 12. A tube 13 leads from the chamber inclosed by this body and is adapted for connection with the vessel containing the gas or vapor, the pressure of which is to be measured.

Lead-in wires or conductors 14 and 15 are sealed into the stand 11 and their inner ends are bent to provide over-lapping supporting

terminals 16 disposed one behind the other. The stand is provided with a laterally offset extension or tube 17 in the upper end of which is sealed one end of a supporting rod 60 or wire 18, the opposite end of which is bent downwardly and laterally to provide a supporting terminal 19 disposed vertically above the terminal 16 of one of the lead-in wires. A thin fixed strip or filament 20 of 65 suitable metal has its intermediate portion passed over the supporting arm 19 and its terminals secured to the overlapping ends of the lead-in wires 14 and 15 in the manner best shown in Fig. 2, so that it is held under 70 tension and one stretch of the filament is disposed vertically and axially within the chamber. Obviously, a current passed between the lead-in wires through the strip or filament will heat it in proportion to the 75 resistance which it offers to the circuit.

For the sake of extreme delicacy, supporting wires or rods 21 and 22 may be substituted for the lead-in wires 14 and 15 as the supports for the filament, and relatively 80 light lead-in wires 23 may be sealed into the bottom of the body 10 and connected to the filament immediately beyond the joints of the filament with the supporting wires 21 and 22 so that the relatively large joints 85 necessary for sufficient strength to support the filament will not form part of the circuit, and their resistance will not enter into the problem. Such an arrangement is shown in Fig. 3 and either construction may be 90 employed as deemed advisable.

Sealed into the top of the body 10 is a supporting rod or wire 24 which extends axially of the body and which, at its lower end, is doubly off-set to provide a supporting arm 25 disposed in parallel and horizontal spaced relation to the supporting arm 19 and in juxtaposition thereto. Secured at one end to the supporting arm 25, so as to normally hang by gravity in parallel close 100 relation to the vertical stretch of the filament 20, is a movable metallic filament or strip 26. This strip may be formed from gold leaf or may consist of a fine quartz fiber metallically coated with some suitable 105 metal, such as platinum.

In operation, the tube 13 is connected to the vessel containing the gas or vapor, the pressure of which is to be measured, and a measured electric current is sent through the 110 lead-in wires and heating strip or filament 20. A suitable instrument (not shown) is

connected in this circuit so that the changes in resistance offered by the filament 20, which constitute a measure of the temperature of such filament, may be determined, and the deflection of the movable strip 26 is carefully noted. Of course, the deflection of this movable strip is caused by its molecular bombardment by the molecules of the gas or vapor being measured, under the influence 10 of the heat of the vertical strip of the filament 20. The amount of deflection of the moving part is proportionate to the density of the gas or vapor being measured and, by carefully measuring this deflection, the 15 density may be determined by employment of a proper formula. Such a formula is:

$$P = K \frac{S}{T_2 - T_1}$$

20 where

P is the pressure

S is the deflection

T_1 is the original temperature

T_2 is the final temperature,

25 the temperatures being measured by the resistances, and K is a constant for the gage.

This constant K may be derived from suitable calculations, as will be readily appreciated by any one skilled in the art or by direct 30 comparison of the gage with a standard or previously calibrated gage, such as a gage of the Knudsen type. This comparison of the gages should, however, be with a gas or vapor at a pressure near the upper range of 35 my improved gage, that is, near the lower range of the Knudsen gage as, above such a pressure, accuracy would not be obtained. The range of operation of a number of gages constructed in accordance with my invention, 40 within which the calibration is linear is from 10^{-7} to 10^{-4} mm. Above the latter pressure, special calibration is required.

To neutralize static charges, the rod or wire 24 may be connected externally to one 45 of the lead-in wires 14 and 15 and, of course, in use, the body of the instrument, save for a sight opening, will be wrapped in foil.

It will, of course, be clear that numerous 50 changes in construction and arrangement of parts, particularly in the supports for the fixed film or filament and for the moving film or strip, may be made and I, therefore, reserve the right to make any changes in construction which shall fall within the 55 scope of the claims.

I claim as my invention:

1. A gage for measuring low pressures of 60 gases or vapors including a vessel providing a chamber, a conductor element fixed within the vessel, means for passing a current through the conductor element to heat it and an element freely supported for swinging movement and normally in parallel spaced relation to the conductor element.

2. A gage for low pressures including a vessel providing a chamber, a metallic strip supported in fixed position within the vessel, means for passing a current through the strip and a metallic strip supported at one end within the vessel for swinging movement and normally hanging in close parallel relation to the first strip. 70

3. A gage for low pressures including a vessel providing a chamber, a conductor strip fixedly secured within the chamber in vertical position, means for passing a current through the strip, and a movable strip or vane suspended from one end within the chamber and normally in close parallel relation to the conductor strip. 75

4. A gage for low pressures including a vessel providing a chamber, a tube communicating with the vessel and adapted for connection with a chamber containing the gas or vapor, the pressure of which is to be measured, a supporting rod extending into the chamber, lead-in wires extending into the chamber, a metallic strip or ribbon having its ends connected to the lead-in wires and its intermediate portion supported under tension by the supporting rod with one stretch of the strip vertically disposed, a second supporting rod extending into the chamber and a second strip or vane secured at one end to the second supporting rod and depending for free swinging movement, the second strip being normally adjacent and parallel to the vertical stretch of the first strip. 85

5. A gage for low pressures including a hermetically sealed vessel having a branch tube adapted for connection to a vessel containing the gas or vapor, the pressure of which is to be measured, a conductor element supported in fixed position within the vessel, 90 means for passing a current through such element and a vane suspended in parallel spaced relation to the conductor element. 95

6. A gage for low pressures including a hermetically sealed vessel having a branch tube adapted for connection to a vessel containing the gas or vapor, the pressure of which is to be measured, a conductor element supported in fixed position within the vessel, means for passing a current through such element and a vane suspended in parallel spaced relation to the conductor element, the vane being formed of gold leaf. 110

7. A gage for low pressures including a vessel providing a chamber, a movable strip or vane suspended within the chamber and electrically heated means for causing molecular bombardment of the vane. 120

In testimony whereof I have hereunto 125 subscribed my name this 26th day of Dec., 1917.

JAMES E. SHRADER.
